STOVE

Herman Herrenbruck, Belleville, Ill., assignor to Orbon Stove Co., Belleville, Ill., a corporation of Delaware

Application December 2, 1931, Serial No. 578,474

1 Claim. (Cl. 126—1)

This invention relates to stoves; and has special reference to stoves constructed to use solid fuels.

The present invention is embodied in a stove having a fire box or combustion chamber constructed and arranged for the optional use of coal or wood as fuels. The coal and similar fuels are delivered into the combustion chamber or fire box through the top, while fuel wood is delivered into the combustion chamber or fire box through an opening at one end thereof. The stove includes a removable wall at one end of the combustion chamber or fire box which is kept in place and used when coal is used as fuel and is removed and kept out of use when wood is used as fuel.

The stove includes a door opposite the opening at the end of the fire box through which the fuel is fed into the stove, so that the door must constitute a closure for the end of the fire box when wood is used as fuel and the removable wall constitutes the end of the fire box when coal is used as fuel.

An object of the invention is to provide an improved device in connection with the door forming a closure for the end of the fire box when wood is used as fuel and which does not interfere with the use of the removable wall at the end of the fire box to convert the fire box into an arrangement adapted to use coal as fuel. This improved device in connection with the door functions to prevent the wood ashes from dropping out at the end of the fire box and also to protect and prevent overheating of the door, thus protecting the enamel and ornamental finish on the door from the excessive heat to which it would otherwise be subjected.

Other objects will appear from the following description, reference being made to the accompanying drawing, in which—

Fig. 1 is a front elevation of a portion of a stove, the door being open showing the removable wall in place to adapt the fire box for use of coal as fuel.

Fig. 2 is a vertical sectional view at right angles to Fig. 1 showing the construction and arrangement of the door and the removable wall, the door being closed and the removable end wall in position.

Fig. 3 is a view similar to Fig. 1 showing the opening to the fire box obtained by removal of the removable wall to permit wood fuel to be fed into the fire box.

Fig. 4 is a vertical sectional view similar to Fig. 2 but having the removable end wall removed.

The stove in which the present invention is shown comprises a top frame 1 having openings 2 therethrough above the fire box 3. It is a familiar fact that these openings 2 are usually

closed by lids which may be removed to permit coal fuel to be delivered into the fire box and which also may be removed to permit cooking utensils to be substituted therefor. But the removable lids may be kept in place, if desired, so as to close the upper side of the fire box. The bottom of the fire box is closed by arcuate grates 4 which may be turned to position in which their curved surfaces are upward when coal is to be used as fuel, or to position in which their convex surfaces are upward when wood is to be used as fuel, or vice versa.

The front of the stove includes a frame 5 rigidly attached to the top frame 1 by fasteners 6. At the front of the fire box 3 the frame 5 includes the upper portion of a door frame consisting of a flange 7 extending upwardly at the bottom, downwardly at the top and inwardly at the sides of the opening through the front of the frame 5. The flange 7 at the sides of the frame 5 is connected by a cross member 8 extending across the opening through the frame 5 at the front of the fire box 3. The opening 9 thus formed through the frame 5 at the front of the fire box is surrounded by a flange 10 projecting upwardly from the cross connection 8 and extending upwardly along the sides of the opening through the frame 5 and across the upper end of said opening. This flange 10 is spaced inwardly from the outer edges of the flanges 7 and 8 and constitutes a seat designed and adapted to receive a closure member 11 constituting an important feature of the present invention.

A door frame is angular in cross section including a vertical portion 12, and an inwardly extended portion 13 is pivotally mounted in connection with the frame 5 by hinge members 14. The flange 13 of this door frame is adjacent to or against the flange 7 when the door is closed, while the outer surface of said flange 13 is close to the wall 15 of the opening in which the door is mounted, thus permitting the outer surface of the flange 12 to be in approximate continuation of the outer surface of the adjacent portion of the frame 5 or stove wall. The upper portion of the door frame has a number of inwardly extended spaced lugs 16 formed with screw threaded holes. The member 11, which is a solid metallic plate, seats against the inner ends of the lugs 16 and is attached thereto by removable and replaceable screw fasteners 17. This plate, as stated, fits in the frame in the front of the fire box that includes the cross member 8 and the flanges 10. The plate 11 is formed with a marginal inwardly extending flange 18 designed and adapted to approach closely to or abut against the flange 10 so as to form a closure at the front of the fire box, protecting and shielding the door from excessive heat and also preventing the dropping of

ashes from the fire box. This plate 11 is spaced substantially from the sheet metal door panel 19 that is engaged with and secured in the opening through the frame 12 by clips 20. These clips 20 are attached to the door frame by removable and replaceable fasteners 21 and said clips engage inwardly and outwardly turned marginal portions 22 formed along the edges of the panel 19 and extending along the inner side of the door frame portion 12.

10 A removable wall 23 is a solid plate designed and adapted to seat upon a supporting wall 24 across the lower portion of the fire box and against a shoulder 25. The wall 24 is integrally 15 united with the cross member 8. The plate 23 inclines upwardly and outwardly and has across its upper edge an outwardly curved portion 26 extending over the flange 10 and abutting against the frame 5. This plate has holes 27 through 20 its upper portion permitting the passage of air into the fire box and also has a number of inwardly extended lugs 38 which may be manually engaged in handling the plate in the placement or removal thereof.

25 The door thus provided constitutes a closure or cover for the space at the front of the ash pan 29 which is mounted below the fire box in order to receive the ashes dropping through the grate and also covers the front ends of the rocker supports 30 and 31 for the grate members, the front 30 ends of which are supported for rocking movements by a plate 32 attached to the frame 7 by a stove bolt 32'. The rocker support 30 projects outwardly below the wall 24 and below and beyond 35 the outer edge of the member 8 so that the end of said support is easily engageable (Fig. 2). The door has a handle device 33 whereby the door may easily be opened and closed and has a spring latch 34 arranged to engage a hook catch 35 attached to the plate 32.

40 It must now be clear that this invention comprises an efficient and simplified construction in a stove having a fire box arranged to use either coal or wood as fuel at the option of the user.

The stove may easily be adapted and arranged to use coal as a fuel simply by placing the plate 23 in the position shown and described, the coal fuel being fed through the openings 2. Simply by removing the plate 23, the stove may be converted into a wood burning stove and the wood fuel may easily be fed through the opening at the front of the fire box. The device 11 cooperates efficiently in both uses of the stove and is a baffle to protect the door panel 19 from excessive heat at all times. It also serves at all times to prevent the ashes from dropping down the front of the stove and is an efficient closure for the front of the fire box when wood is used as fuel.

10 The construction and arrangement of the parts of the invention may be varied within the scope of equivalent limits without departure from the nature and principle of the invention.

15 I claim:

In a stove having a firebox at the upper portion thereof, grates for supporting fuels in said firebox, a waste receptacle below said grates, a vertically elongated frame at the front of the stove affording access to said firebox and to said waste receptacle, a cross member connecting the 20 sides of said frame and coacting with said frame to define a firing opening to said firebox and a clean-out opening to said receptacle, an inwardly positioned sealing flange in connection with that portion of said frame and said cross member defining the firing opening, a wall extending downwardly and inwardly from said cross member, a rocker arm for one of said grates extending outwardly through said wall and beyond the vertical plane of said cross member, a door including a 25 door frame hinged to said first named frame and a panel attached to said door frame, said door coacting with said first named frame to close both of said openings, and a plate carried by the upper inner surface of said door and coacting with said sealing flange when the door is closed 30 to seal said firing opening.

35 HERMAN HERRENBRUCK.
